REFRIGERATING APPARATUS

Marshall W. Baker, Dayton, Ohio, assignor to
 General Motors Corporation, Dayton, Ohio, a
 corporation of Delaware

Application September 24, 1937, Serial No. 165,552

11 Claims. (Cl. 62—3)

This invention relates to refrigerating apparatus and heat transfer apparatus and more particularly to liquid control means.

It is a difficult problem to provide a desirable and satisfactory control for controlling the flow of liquid refrigerant from the liquefying means to the evaporating means in a refrigerating system. This is demonstrated by the fact that so many different types of controls are used and so many more have been devised but little used.

It is an object of my invention to provide a simple, dependable liquid control which is more rapid in its response to changes in conditions in the refrigerating system than other types such as the thermostatic type.

It is another object of my invention to provide a liquid control which is extremely sensitive to an excess of liquid refrigerant in the evaporating means.

It is another object of my invention to provide a diaphragm operated valve means for a refrigerating system in which both sides of the diaphragm are exposed to refrigerant in the system.

It is a still further object of my invention to provide a means for preventing the flooding of the evaporator during idle periods of the compressor when an elongated orifice is employed as a liquid control.

Further objects and advantages of the present invention will be apparent from the following description, reference being had to the accompanying drawing, wherein a preferred form of the present invention is clearly shown.

In the drawing:

Fig. 1 is a diagrammatic representation of a refrigerating system including one form of my control means shown in section;

Fig. 2 is a diagrammatic representation of a refrigerating system including another form of my control means shown in section.

Briefly, in the first form of my invention, I have shown a pressure operated valve in series with a restrictor which is biased to closed position by a spring, but opened by the pressure differential existing between the inlet and the outlet of the evaporating means. In the second form, I have shown a valve which may or may not be used in connection with a restrictor, and which is biased to closed position and opened by the pressure differential between the inlet and the outlet of the evaporating means and, in addition, has a cup provided with a small orifice at the bottom so as to collect any liquid flowing out of the evaporating means to act as a sensi-

tive actuator to close the valve whenever liquid is discharged from the evaporating means. The third form reverses the second form to cause opening of the valve when there is no pressure difference or when liquid is in the cup.

Referring now to the drawing, and more particularly to Fig. 1, there is shown a liquefying means including a compressor 20 for compressing refrigerant and for forwarding the compressed refrigerant to a condenser 22 where the compressed refrigerant is liquefied and collected in a receiver 24. From the receiver 24, the liquid refrigerant is forwarded through a supply conduit 26 to a restrictor or elongated orifice 28 provided for controlling the flow of liquid refrigerant into the evaporating means. In prior systems, the outlet of the restrictor has been connected to the inlet of the evaporating means 30, where the refrigerant evaporates under reduced pressure and is returned to the compressor through the return conduit 32. The compressor 20 is driven by an electric motor 34 under the control of a snap-acting switch means 36 actuated by a fluid pressure system responsive to the temperature of the evaporating means 30.

In such a system, during the idle period, considerable amounts of refrigerant are forced through the restrictor into the evaporator means. After all of the liquid is drawn out of the receiver, warm uncondensed gas from the condenser and receiver may pass through the restrictor into the evaporating means. This warm gas discharged into the evaporator under such conditions is very detrimental to the efficiency of the refrigerating system. The flooding of the evaporator with liquid refrigerant during the idle period may cause trouble at the beginning of the next running period since under such conditions some liquid refrigerant may be drawn from the evaporator into the compressor and thereby damage the compressor. The discharge of liquid refrigerant into the evaporating means during the idle period is also somewhat detrimental to the efficiency of the system. The amount the efficiency is reduced by this liquid and gas flow during the idle period of the system depends upon the refrigerant used. For example, when sulphur dioxide is used in the system, there is a serious loss in efficiency by this flow during the idle period. However, when difluoro-tetrafluoro-ethane is used as the refrigerant, this loss is comparatively small and is compensated for by the simplicity of the system.

This refrigerant, however, is much more expensive than sulphur dioxide and I have, there-

fore, provided a valve generally designated at 38 which is connected to the outlet of the restrictor and to the inlet of the evaporating means for shutting off the flow of fluid from the restrictor to the evaporating means during idle periods of the system. This valve is provided with a casing formed of a cup-shaped member 40 which is provided with a lid 42. The cup-shaped member 40 is provided with an entrance 42 connected to the outlet of the restrictor 28 which is provided with a valve seat. The valve needle 44 comes into engagement with the seat during idle periods. This valve needle 44 is formed as a projection from the end plate provided upon a bellows 48, which has its opposite end connected to and sealed to the lid 42. The cup-shaped member 40 has a side outlet 50 which is connected to the inlet of the evaporator 30. The lid 42 is provided with a passage 52 extending into the interior of the bellows and provided with external threads which receive a flare nut which connects the passage 52 with tubing 54 which connects to the outlet of the evaporating means 30. The interior of the bellows 48 contains a relatively light coil spring 56 extending between the lid 42 and the end plate 46 for urging the valve needle 44 into position upon its seat.

When the switch 36 is opened, and the system is idle, the pressure at the inlet and the outlet of the evaporating means is the same so that the pressure upon the opposite sides of the bellows 48 and its end plate 46 will be the same. Therefore, there will be no opposition to the coil spring 56 which will then hold the valve needle 44 in closed position. When the evaporator 30 becomes warm, the switch 36 is closed, thus placing the system in operation. The compressor 20 will draw evaporated refrigerant from the evaporator 30 through the return conduit 32. This will cause a gradually increasing pressure differential between the inlet and the outlet of the evaporating means and when the compressor approaches full speed, the pressure differential between the exterior and the interior of the bellows 48 and its end plate 46 will be sufficient to overcome the force of the spring 56 to hold the valve needle 44 in open position. When the system stops its operation, the pressures on opposite sides of the bellows 48 and its end plate 46 will be again equalized, and the spring 56 will return the valve needle 44 to closed position. In this way, the flooding of the evaporator during idle periods is prevented while the operation of the system during normal running periods is not interfered with.

In Fig. 2, a very similar system is shown with the exception that no restrictor is shown, but one may be employed in a manner similar to that shown in Fig. 1 if desired. In this system, there is provided a compressor 60 for compressing the refrigerant, a condenser 62 for condensing the refrigerant and a receiver 64 for collecting the condensed refrigerant. The condensed refrigerant is forwarded through a supply conduit 66 to an interchanger 68 and from the interchanger, the condensed refrigerant is forwarded through a conduit 70 to a modified form of valve 72. If desired, the supply conduit 70 may have a sufficiently small cross-section as to serve as a restrictor. The outlet of my valve 72 is connected through a conduit 74 to the inlet of the evaporating means 76. The outlet of the evaporating means 76 is connected by the conduit 78 to a portion of the valve 72 and this portion of

the valve 72 is connected by the conduit 80 to the interchanger 68 where the evaporated refrigerant removes heat from the condensed liquid passing from the conduit 66 to the conduit 70 and is then returned to the compressor through the return conduit 82.

The valve 72 is provided with a casing having a cup-shaped casing member 84 which receives a second cup-shaped casing member 86 which, together, enclose a cylindrical chamber. The cup-shaped casing member 84 has an inlet passage 88. Connected to the liquid supply conduit 70 is a side outlet passage 90 connected to the conduit 74 leading to the inlet of the evaporating means 76. The interior of the casing is divided into a chamber 92 connected to the inlet of the evaporating means and a chamber 94 connected to the outlet of the evaporating means. These two chambers are divided by a bellows 96 having an end plate 98 to which is fastened a needle valve 102 for closing the inlet passage 88. The bellows 96 has its end opposite the end plate connected to and sealed to the rim of the cup-shaped casing member 86.

Within the chamber 94 beneath the inlet 104 to which the outlet of the evaporating means 76 is connected by the conduit 78, there is provided a cup-shaped portion 106 provided with a small aperture 108 in its bottom portion. This cup-shaped portion 106 is formed upon the end of a lever 110 pivoted at 112 to the cup-shaped casing member 86 and having an arm 114 extending downwardly so as to engage the end portion of the valve needle 102 which extends a considerable distance upon both sides of the end plate 98.

The compressor 60 is driven by an electric motor 116 under the control of a snap acting switch means 118 controlled through a fluid pressure system in response to the temperature of the evaporating means 76. When the switch 118 is open, and the system is idle, no pressure differential will exist upon opposite sides of the bellows 96 and its end plate 98, and, under such conditions, the weight of the cup-shaped portion 106 will be sufficient to move the needle valve 102 into position upon its seat to prevent the flow of liquid refrigerant into the evaporating means.

When there is a demand for refrigeration, the switch 118 will close, and the compressor will operate, thereby creating a pressure difference upon opposite sides of the bellows 96 and its end plate 98, thereby overcoming the weight of the cup-shaped portion 106 to permit the valve 102 to open. This will allow liquid refrigerant to flow into the evaporating means and will permit such flow until liquid refrigerant or lubricant or a mixture of liquid refrigerant and lubricant is discharged through the passage 104 into the cup-shaped portion 106. Such a discharge of liquid into the cup-shaped member 106 will overcome the pressure differential existing upon the bellows 96 and its end plate 98 and cause the valve needle to be moved to closed position in which it rests upon its seat. This will prevent the further supply of liquid refrigerant until the refrigerant and lubricant escape from the cup-shaped portion 106 by evaporation or by passing through the orifice 108 from which it returns to the compressor through the conduit 80 to the heat interchanger 68 and the conduit 82. The interchanger 68 has a capacity to evaporate refrigerant at a rate exceeding the rate at which refrigerant can pass through the orifice 108.

Any liquid refrigerant discharged from the cup-shaped member 106 and passing through the conduit 80 will be evaporated within the heat interchanger so that no liquid refrigerant will pass into the compressor, and, thus, any damage to the compressor will be prevented. This arrangement will be much more sensitive to excess refrigerant in the evaporating means than the usual thermostatic expansion valve which has the thermostat bulb positioned upon the outlet of the evaporating means. Such a thermostat bulb is ordinarily slow to act in case of excess refrigerant because it depends upon changes in temperature which must affect the fluid pressure system which controls the thermostatic expansion valve. The cup-shaped portion 106 acts instantly, because it is directly acted upon by the liquid refrigerant. This valve also keeps the evaporating means filled with liquid refrigerant and thus makes the evaporating means operate at full capacity whenever the system is in operation, and thereby obtains the highest efficiency from the system.

It should be noted that the bellows in both forms of valves are exposed only to refrigerant upon both sides. Therefore, should the bellows leak, no refrigerant will escape from the system and if the leak is small the operation of the valve will not be materially affected.

It should also be noted that my valve is independent of the evaporator temperature and pressure employed since it merely depends upon the pressure drop between two portions of the evaporator for its operation.

While the form of embodiment of the present invention as herein disclosed constitutes a preferred form, it is to be understood that other forms might be adopted, all coming within the scope of the claims which follow.

What is claimed is as follows:

1. Refrigerating apparatus including liquefying means and evaporating means, valve means responsive to the pressure differential between two portions of the evaporating means for controlling the flow of liquid refrigerant from the liquefying means to the evaporating means, and a means forming an elongated orifice located in series circuit relation to the valve means for additionally controlling the flow of liquid refrigerant from the liquefying means to the evaporating means.

2. Refrigerating apparatus including liquefying means and evaporating means, valve means responsive to the pressure differential between two portions of the evaporating means for controlling the flow of liquid refrigerant from the liquefying means to the evaporating means, and a means mechanically responsive to a mechanical aspect of the flow of liquid at the outlet of the evaporating means for controlling the flow of liquid from said liquefying means to said evaporating means.

3. Refrigerating apparatus including a liquefying means and an evaporating means, means forming an elongated orifice for controlling the flow of liquid refrigerant from the liquefying means to the evaporating means, and pressure operated means for shutting off the flow of refrigerant through the orifice during idle periods of the liquefying means, said pressure operated means including means responsive to the pressure differential between the two portions of the evaporating means for opening the orifice to the flow of refrigerant when the liquefying means operates.

4. Refrigerating apparatus including liquefying means and evaporating means, valve means for controlling the flow of liquid refrigerant to the evaporating means, a diaphragm means for operating said valve means, one side of said diaphragm means being subject to the pressure of the refrigerant at the inlet of the evaporating means and the other side of said diaphragm means being subject to the pressure of the refrigerant at the outlet of the evaporating means, said valve means being movable to open position when the pressure of the refrigerant at the outlet of the evaporating means is less than the pressure of the refrigerant at the inlet of the evaporating means, and an additional means for the control of the flow of liquid refrigerant from the liquefying means to the evaporating means.

5. Refrigerating apparatus including a closed circuit containing liquefying means and evaporating means, valve means for controlling the flow of refrigerant from the liquefying means to the evaporating means, diaphragm means for moving said valve means to open position when the refrigerant pressure at the outlet is less than the pressure at the inlet of the evaporating means, said diaphragm means upon the side tending to move the valve means to open position being subject to the pressure of the refrigerant at the inlet of the evaporating means, the opposite side of said diaphragm means being subject to the pressure of the refrigerant at the outlet of the evaporating means.

6. Refrigerating apparatus including a closed circuit containing liquefying means and evaporating means, valve means for controlling the flow of refrigerant from the liquefying means to the evaporating means, diaphragm means for moving said valve means to open position when the refrigerant pressure at the outlet of the evaporating means is less than the pressure at the inlet of the evaporating means, said diaphragm means upon the side tending to move the valve means to open position being subject to the pressure of the refrigerant at the inlet of the evaporating means, the opposite side of said diaphragm means being subject to the pressure of the refrigerant at the outlet of the evaporating means for closing the valve means to the flow of liquid refrigerant into the evaporating means.

7. A heat transfer means including a closed circuit containing liquefying means and evaporating means, means for controlling the flow of fluid through said closed circuit, and means including a diaphragm and a movable cup-shaped member mechanically connected to said diaphragm and said controlling means located at the outlet of said evaporating means so as to collect liquid issuing from the evaporating means for regulating said controlling means.

8. A heat transfer means including a closed circuit containing liquefying means and a dry expansion type of evaporating means, an expansion valve located at the inlet of the evaporating means for controlling the flow of fluid into the evaporating means, and means including a movable cup-shaped member operatively connected to said expansion valve and located beneath the outlet of the evaporating means so as to collect liquid issuing therefrom for controlling the operation of said expansion valve.

9. A heat transfer means including a closed circuit containing liquefying means and a dry expansion type of evaporating means, an expan-

sion valve located at the inlet of the evaporating means for controlling the flow of fluid into the evaporating means, and means including a movable cup-shaped member operatively connected to said expansion valve and located beneath the outlet of the evaporating means so as to collect liquid issuing therefrom for controlling the operation of said expansion valve, said cup-shaped member being provided with a small orifice for draining the cup-shaped member at a relatively slow rate.

10. Refrigerating apparatus including liquefying means and evaporating means, valve means responsive to the pressure differential between two portions of the evaporating means for controlling the flow of liquid refrigerant from the

5 liquefying means to the evaporating means, and means mechanically responsive to the weight of the liquid refrigerant issuing from the outlet of the evaporating means for controlling the flow of liquid from said liquefying means to said evaporating means.

11. A heat transfer means including a closed circuit containing liquefying means and evaporating means, means for controlling the flow of fluid through said closed circuit, a movable cup-shaped member located at the outlet of said evaporating means so as to collect liquid issuing from the evaporating means, and means for operatively connecting said cup-shaped member to said controlling means.

MARSHALL W. BAKER.
